CLAIM

The ornamental design for a garment steamer, as shown and described.

DESCRIPTION

FIG. 1 is a perspective view of a garment steamer, showing my new design;

FIG. 2 is a right-side elevational view thereof;

FIG. 3 is a left-side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view of a second embodiment of a new design of a garment steamer;

FIG. 9 is a right-side elevational view thereof;

FIG. 10 is a left-side elevational view thereof;

FIG. 11 is a top plan view thereof;

FIG. 12 is a bottom plan view thereof;

FIG. 13 is a front elevational view thereof; and

FIG. 14 is a rear elevational view thereof.
